UNITED STATES PATENT OFFICE.

ALGERNON S. SEVILLE, OF MEMPHIS, TENNESSEE.

PERFORATION-SPACING DEVICE.

SPECIFICATION forming part of Letters Patent No. 738,852, dated September 15, 1903.

Application filed February 24, 1903. Serial No. 144,855. (No model.)

To all whom it may concern:

Be it known that I, ALGERNON S. SEVILLE, a citizen of the United States, residing at Memphis, Shelby county, State of Tennessee, have 5 invented certain new and useful Improvements in Perforation - Spacing Devices, of which the following is a specification.

My invention relates to certain new and useful improvements in perforation - spacing devices, and has especial reference to a spacing device to determine the locations of the perforations in the tune-sheets to be used directly in mechanical music instruments, especially those designed for playing the piano, 15 or for the stencil-sheets to be used in the manufacture of such tune-sheets.

The objects of my invention are, first, to provide a simple and efficient metronome which will be capable mechanically of adjustment without technical knowledge of the subject; second, to provide a metronome which will accommodate the entire possible range of tempo in music; third, to provide simple means of shaping the sheet ready for insertion in the device and in the piano-player; 25 fourth, to provide an efficient yet simple clamp for the sheet; fifth, to provide a scale for accidentals; sixth, to provide means of preventing accidental cutting of notes in the wrong spaces, and, seventh, to generally improve the details of these parts.

I accomplish these objects, as will be more fully hereinafter set forth in the drawings, specification, and claims.

Figure 1 is a plan of the device. Fig. 2 is a sectional elevation on the line II II of Fig. 1 looking in the direction of the arrow. Fig. 3 is a sectional elevation on the line III III of Fig. 1 looking in the direction of the arrow. Fig. 4 is a plan and elevation of a detail. Figs. 5, 6, and 7 show manner of arranging the cross or metronome cords for three-four, four-four, and six-four time, respectively.

Referring now to the drawings, in which like numerals indicate the same or like parts in all the views, 11 are side pieces of a frame, (not otherwise shown,) which supports a number of wires 2, spaced equally and of a distance apart corresponding with the space between the holes in the tracker-board of the "player" on which the sheet is to be used.

If, for instance, there are fifty-six to be operated by the player, there must be fifty-six spaces, and therefore fifty-seven wires, on the 55 perforator. A smaller number is shown for purposes of convenience only. The method of supporting the wires and the sheet to be operated on is more fully set out in my Patent No. 720,075, dated February 10, 1903, for 60 a perforation-spacing device.

3 is a scale by which each space between wires is designated. This scale has a plurality of faces 4, any one of which may be placed as is the one here shown, but which is 65 not described, since it is not desired to make it a part of this application. In this scale, however, middle C is marked by an arrow or other indicator, as shown, and the base and treble clefs are also indicated. Coming directly in front of the edge of the face 4 of this scale is a fixed wire 5, which is stretched across at right angles to the wires 2, which give the pitch, which wire serves as an index or base for the tempo-divisions. 66 are elastic bands 75 stretched across parallel to this base-wire, which divide the spaces longitudinally or for time. As shown, these bands give two beats or a single measure of two-two or two-four time. These bands 6 are carried at each end 80 by notched pins 7, the shanks 8 of which connect together pieces 9 10 to form lazy-tongs, one for each side of the device. These shanks extend downward below the pieces 9 10 and rest in a groove 11, in which they are free 85 to slide. The piece 9, however, at the left end of each pair of the tongs is fastened into the frame, as shown. This is preferably effected by using a screw 12, the notch in the head of which serves as a rest for the index-wire 5. The piece 10 at the right-hand end of each pair of the tongs is fastened by their pin-shanks 8 into racks 13, which slide in the same grooves 11 as do the said pin-shanks and which are moved by pinions 14 on a shaft 95 15, actuated by a thumb-wheel 16.

17 is a pointer on one of the racks 13, and 18 is a scale, preferably marked, as shown, "Allegro," "Allegro moderato," "Andante," and "Largo." When, therefore, the music 100 is written "Allegro," the scale-pointer 17 is brought to this position. If written in other time, it is brought to the position desired, thus mechanically relieving the operator of

trouble in the matter. As will be seen, the lazy-tong movement will proportion the distance between the pins 7, and therefore will give equal spaces between each, and therefore between the bands on same. Since, also, the index-wire is placed on one of the pins, the space between it and the cross-bands and between the cross-bands themselves is equal. The pointer 17, therefore, being moved, the spaces between the bands and between the index and bands increases or decreases proportionately.

19 is a casing to cover and hold down the outer ends of the lazy-tongs. This casing is shown removed on one side of the device to show the entire tongs. If desired to use this spacing device for more than six beats, the tongs may be extended to the dotted position shown and bands strung on the pins 7 and also on the center rows of pins 20, thereby giving, if desired, twelve beats of twelve-eight time or any desired lesser number. It would be possible also to cut faster or slower time than the ordinary range of the device by this means. In Fig. 5 I show the arrangement of the cross-bands 6 for three beats or one measure of three-four or three-eight time. Fig. 6 shows the same arrangement for four beats or one measure of four-four or four-eight time. Fig. 7 shows a measure of six-four or six-eight time. Fig. 4 shows a plan elevation and end elevation of a modified form 10_a of the top piece of the lazy-tongs. In this a lug 20_a is punched and turned up in lieu of the pin 20, and the end 7_a is turned up instead of the pin 7. The pieces 9 and 10_a are then riveted together. In this case it is necessary to get the pieces 20_a and 7_a as nearly as possible over the rivets in order that their proportionate distance from the index-wire 5 may remain as nearly constant as possible.

21 is a fixed scale having the scale-letters A, B, C, D, E, F, G in order corresponding with the white keys of the piano, and the black keys (the sharps and flats) represented by shaded sections. This scale is used for accidentals. The paper is held for cutting by a clamp comprising a cylindrical casing 22, having an inverted flange at the bottom supporting a spring 23, which bears against the under side of the button-head 24 on a pin 25. This pin is depressed by a cam 26, pivoted at 27 and having an arm 28, extending outward therefrom. This cam is preferably so located with reference to the button 24 that it releases it entirely only when straight out over the cutting-board of the device, so that it will interfere to a greater or less extent with the operation of perforating the paper unless the same is locked. This locking is done by swinging the arm in the direction of the arrow about ninety degrees, and thereby depressing the pin 25.

29 is a triangular sheet of metal shaped to conform to the required shape of the ends of the paper to be used in the piano-player, which is supported at one or both sides just clear of the

board 30, which serves as a music-rest. The end of the paper is slipped under this from one side or one end, as the case may be, and is then torn by this piece to the desired shape. In use the paper is pointed as just described, any desired fastenings are put on it, and it is slipped to place beneath the wires 2. The arm 28 is then moved to clamp the paper, the desired number of cross-bands are placed, and the pointer 17 is moved to the desired time, as shown by the tempo-scale 18. The several notes constituting the measure are then cut in their proper positions as regards pitch and time and the clamp is loosened and the paper slipped forward until the last note cut comes against the index-wire. The clamp is then reset and the operation repeated.

In order to guard against the danger of cutting a note against the index-wire, and therefore incorrectly, I provide a strip of celluloid 31, which fills the space between the index-wire 5 and the first band 6. This strip being transparent permits the wires to be seen beneath it and therefore easily followed from the pitch-scale. 32 is the paper to be cut.

Having fully described my invention, what I claim, and desire to secure by Letters Patent of the United States, is—

1. In a perforation-spacing device, the combination with the side frames, of a board supported from said side frames to form a music-rack, and a flat triangular piece supported at its edges from said board and being just clear of the same, substantially as shown and described.

2. In a perforation-spacing device, a tempo-indicating device, comprising duplicate pairs of lazy-tongs, bands carried by said lazy-tongs, and means of extending said tongs to change said time from fast to slow, substantially as shown and described.

3. In a perforation-spacing device, a tempo-indicating device comprising duplicate pairs of lazy-tongs, bands carried by said lazy-tongs and racks for extending same to change said time from fast to slow, substantially as shown and described.

4. In a perforation-spacing device, a tempo-indicator comprising duplicate pairs of lazy-tongs, having one end of each fixed, an index-wire carried by said fixed points, cross-bands stretched between corresponding points on said tongs and means for extending or shortening said tongs, to make the time slower or faster, substantially as shown and described.

5. In a perforation-spacing device, a tempo-indicator comprising duplicate pairs of lazy-tongs, having one end of each fixed, an index-wire carried by said fixed points, cross-bands stretched between corresponding points on said tongs and racks extending or shortening said tongs, to make the time slower or faster, substantially as shown and described.

6. In a perforation-spacing device, as a tempo-indicator, the combination with the perforator-frame and grooves in said frame, of duplicate pairs of lazy-tongs, fixed pivots

5 pivotally connecting said tongs to said frame, racks pivotally attached to the opposite ends of said tongs and slidably mounted in said grooves, pinions actuating said racks, forks carried by said tongs, a fixed or index wire supported by said fixed pivots and bands stretched from corresponding forks on said tongs, substantially as shown and described.

7. In a perforation - spacing device, as a 10 tempo-indicator, the combination with a suitable frame, of lazy-tongs mounted on said frame, cross-bands carried by said tongs, racks and pinions for operating said tongs, a tempo-scale on said frame and a pointer on one of 15 said pairs of tongs, substantially as shown and described.

8. In a perforation - spacing device, as a 20 tempo-indicator, the combination with a suitable frame, lazy-tongs mounted on said frame, a fixed index-wire, cross-bands carried by said tongs and racks and pinions operating said tongs in unison, of a tempo-scale on said frame and a pointer on one of said pairs of 25 tongs, substantially as shown and described.

25 9. In a perforation - spacing device, as a

tempo-indicator, the combination with a suitable frame, lazy-tongs having one end pivotally mounted on said frame, an index-wire fixed at said pivot-mounting, forks projecting upward from said tongs at the joints, elastic 30 cross-bands carried by said forks, means of extending or shortening said tongs, a scale on said frame and a pointer on one of said pairs of tongs, substantially as shown and described.

10. In a perforation - spacing device, the 35 combination with the side frames of a board supported from said frames to form a music-rack, a cylindrical casing through said board, a spring in said casing a pin through said casing and spring having a button-head resting 40 on said spring and an arm for depressing said pin, substantially as shown and described.

In testimony whereof I have signed my name to this specification in the presence of two subscribing witnesses.
